DISPLAY RACK FOR LUGGAGE TAGS OR THE LIKE

John V. Colan, Warwick, R.I., assignor to Crownmark
Corporation, Providence, R.I.

Filed July 23, 1973, Ser. No. 381,670

Term of patent 3½ years

Int. Cl. D20—02

U.S. Cl. D6—151

FIG. 1

FIG. 2

FIG. 3

FIG. 4

FIG. 5

FIG. 6

FIG. 1 is a front elevational view of a display rack showing my new design;

FIG. 2 is a bottom plan view thereof;

FIG. 3 is a rear elevational view thereof;

FIG. 4 is a top plan view thereof;

FIG. 5 is a side elevational view thereof, looking from the right with respect to FIG. 1; and

FIG. 6 is a side elevational view thereof, looking from the left with respect to FIG. 1.

I claim:

The ornamental design for a display rack for luggage tags or the like, substantially as shown.
